US00D811434S

(12) United States Design Patent (10) Patent No.: US D811,434 S
(45) Date of Patent: * Feb. 27, 2018

(54) DISPLAY SCREEN OR PORTION THEREOF WITH ICON

(71) Applicant: SAMSUNG ELECTRONICS CO., LTD., Suwon-si, Gyeonggi-do (KR)

(72) Inventors: Soonkyu Jang, Gwacheon-si (KR); Jueun Lee, Seoul (KR); Suk-Young Woo, Seoul (KR); Eunju Tae, Bucheon-si (KR)

(73) Assignee: SAMSUNG ELECTRONICS CO., LTD., Gyeonggi-Do (KR)

() Term: 15 Years

(21) Appl. No.: 29/566,464

(22) Filed: May 31, 2016

(30) Foreign Application Priority Data

Dec. 3, 2015 (KR) 30-2015-0061528

(51) LOC (11) Cl. 14-04

(52) U.S. Cl. ..... USPC D14/492

(57) CLAIM

The ornamental design for a display screen or portion thereof with icon, as shown and described.

DESCRIPTION

The sole FIGURE is a front view of a display screen or portion thereof with icon showing our new design.

The broken lines in the FIGURE show a display screen or portion thereof, and form no part of the claimed design.

1 Claim, 1 Drawing Sheet
